DESIGN FOR A COMBINED VANITY AND CIGARETTE CASE

William T. Korn, New York, N. Y.

Application September 25, 1945, Serial No. 122,335

Term of patent 7 years

(Cl. D86—10)

To all whom it may concern:

Be it known that I, William T. Korn, a citizen of the United States of America, residing in New York city, county of New York, and State of New York, have invented a new, original, and ornamental Design for a Combined Vanity and Cigarette Case, of which the following is a specification, reference being had to the accompanying drawing, forming part thereof, wherein

Figure 1 is a plan view of a combined vanity and cigarette case showing my new design.

Figure 2 is a side elevational view, and
Figure 3 is a front elevational view of the combined vanity and cigarette case shown in Figures 1 and 2.

I claim:

The ornamental design for a combined vanity and cigarette case, substantially as shown.

WILLIAM T. KORN.
